United States Patent Office

Des. 200,810
Patented Apr. 6, 1965

200,810

BOTTLE

Stanley K. Johns, Toronto, Ontario, Canada, assignor to
St. Lawrence Manufacturing Company, Inc., Giffard,
Quebec, Canada, a corporation of Canada

Filed Aug. 16, 1963, Ser. No. 76,240

Term of patent 14 years

(Cl. D58—6)

Fig.1

Fig.3

FIG. 1 is a front elevation of a bottle embodying my new design;

FIG. 2 is a side elevational view thereof; and

FIG. 3 is a bottom plan view thereof.

The rear, not shown, is substantially like the front shown.

I claim:

The ornamental design for a bottle, as shown and described.
